UNITED STATES PATENT OFFICE.

IRENE NORMAN, OF MEMPHIS, TENNESSEE.

SLEEPING-PORCH.

1,359,418.

Specification of Letters Patent. Patented Nov. 16, 1920.

Application filed October 8, 1919. Serial No. 329,280.

To all whom it may concern:

Be it known that I, IRENE NORMAN, a citizen of the United States, residing at Memphis, in the county of Shelby and State 5 of Tennessee, have invented certain new and useful Improvements in Sleeping-Porches, of which the following is a specification.

This invention relates to sleeping porches, and has for an object to provide a sleeping 10 porch of improved type capable of being attached to and suspended without a window.

A further object of the invention is to provide improved screening means for the porch, whereby the bed supported upon such 15 sleeping porch is protected in the usual manner.

With these and other objects in view, the invention comprises certain new and novel features, combinations and arrangements of 20 parts, as will be hereinafter more fully described and claimed.

In the drawings,

Figure 1 is a view of the improved sleeping porch taken upon a vertical plane intersecting its ends.

Fig. 2 is a perspective, fragmentary view of several of the parts disassociated.

Fig. 3 is a fragmentary, detail, sectional view of one of the corners.

Fig. 4 is a fragmentary view of the means for attaching the device to the window sill.

Fig. 5 is a detail sectional view, showing the manner of adjustment to compensate for walls of different thicknesses.

Like characters of reference indicate corresponding parts throughout the several views.

The improved sleeping porch, which forms the subject-matter of this application, 40 comprises a pair of brackets composed of a beam 10, and a brace member formed of a plate member 11 and a brace 12. The bracket is adapted to be attached to the window sill by having the bar 10 provided

45 with a hook, preferably twisted as indicated more particularly at 13, with a set-screw 14 engaging in a channel bar 15, which extends across the inside of the window sill and is made of sufficient length to accommodate the

50 device to windows of various widths. Also the device is adapted for adjustment to walls of varying thicknesses, by having the beam 10 provided with a plurality of perforations 16, as shown more particularly in Fig. 5, and with bolts 17 extending through the

registering perforations of the beam and the underlying brace member 11.

As the adjustment, just mentioned, would not compensate to a nicety for all thicknesses of wall, a second set-screw 18 is provided, also engaging with a channel bar 19 similar to the channel bar 15, such channel bar being clamped by the set-screws 18 upon the ledge of the window, as indicated more particularly at Fig. 1. By the adjustment 60 provided by the bolts 17, approximate adjustment can be secured, and the complete adjustment secured by the use of the set-screws 14 and 18, to insure that the beam 10 shall be level. 70

Upon the structure produced by the completed bracket, a bed-bottom is positioned comprising pipes 20 extending longitudinally of the bed structure, that is to say, transversely relative to the beams 10. The 75 pipes 20 are of the usual and ordinary lengths providing bed-bottoms, and are provided with upturned extremities 21, as shown more particularly at Figs. 2 and 3. A frame or bar 22, preferably of angle-bar 80 construction, is rigidly secured to the upturned extremities 21, and to such angle-bar structure, the bed-bottom fabric of any construction is secured, being indicated diagrammatically at 23, it being understood 85 that this fabric may be of any usual and ordinary type. The angle rails 22 are also preferably provided with a hinge 24, whereby the structure may be folded with one of the pipes 20 superposed substantially upon 90 or above the other pipe, making the folded bed structure one-half the width of the extended structure. To maintain this bed-bottom structure upon the brackets, hooks 25 are provided, secured upon the pipes 20 95 by means of sleeves 26, with set-screws 27 to maintain the proper position of the parts. By simply sliding the bed-bottom structure forwardly, the hooks are disengaged from the bracket structure, whereby the bed structure may be folded, the mattress indicated in dotted lines at 28 having been first removed. 100

The device, thus constructed, is a complete operative device, but it is desirable to 105 erect about the bed structure a guard. As shown, the guard comprises a frame having a bottom front rail 29, and end-rails 30 with uprights 31 and 32, with a front upper rail 33 and end-rails 34. The area within the 110

frame thus constructed, is filled with any fabric material preferably a coarse and resisting fabric 35 for safety, and the finer insect-resisting fabric 36, whereby the structure protects the user not only against accident, but also against insects. Preferably the uprights 32, which are adjacent the house, are provided with screws 37, although such screws 37 are unnecessary, if a covering is used over the guard, which is desirable to complete protection against insects. such cover, when used, comprises a frame composed of front and rear bars 38, and end bars 39, the end bars being preferably provided with hinges 40, whereby the cover structure may be folded to be withdrawn through the window. Also, of course, the frame structure is covered with such fabric structure as may be found desirable.

20 For the purpose of maintaining the guard structure upon the bed-bottom, brackets 41 are carried by such guard structure, and for the purpose of retaining the cover member upon the guard structure, brackets 42 are provided, and either or both of such brackets may be provided with set-screws or thumbscrews 43, whereby the several parts are held in separable engagement.

In operation, it will be apparent that the 30 bracket members carrying the bars 15 and 19 will first be exserted through the window, and the bracket members adjusted longitudinally of the bars 15 and 19 to the width of the window. The beams 10 are now leveled by the proper adjustment of the screws 14 and 18, whereby the beams 10 are horizontal 35 and in parallelism. The bed-bottom structure folded is now exserted through the window upon the brackets, and extended to its 40 unfolded position. The guard structure, by reason of its height and being provided with three sides, requires no hinging, and may be exserted through the window and properly positioned upon the bed-bottom structure, as likewise the cover member will 45 also be put into place. The sleeping porch and bed arrangement are now complete and the bedding may be placed thereon in the usual well-known manner.

50 I claim:

1. A sleeping porch comprising spaced brackets composed of a plate and brace rigidly connected and a horizontal beam adjustably mounted thereon, means to adjust the tops of the brackets to occupy a horizontal plane, a bed structure comprising a foldable bed-bottom, and means to removably secure the bed-bottom to the brackets.

55 2. A sleeping porch comprising spaced

brackets, means to adjust the tops of the 60 brackets to occupy a horizontal plane, a bed structure provided with a folding panel, hooks adjustably mounted upon the bed structure and adapted to freely engage the brackets to removably secure the bed structure to the brackets, and a guard structure provided with means for engagement upon the bed structure.

3. A sleeping porch comprising brackets 70 embodying a beam and a brace member, and adapted to be secured to a window sill, means to adjust the brace member relative to the beam, means on either side of the window sill to adjust the completed bracket to position the tops of such brackets in a 75 horizontal plane, a bed structure adapted to be carried upon the brackets, a guard structure surrounding the bed structure, and a cover structure carried upon the guard structure.

4. A sleeping porch comprising brackets 80 each comprising a beam and a brace member, means to permit adjustment of the brace member relative to the beam member, means to secure the beam and brace member in 85 such adjusted relation, a hook carried by each of the beam members adapted to hook over a window sill, and adjusting screws carried by the completed bracket adapted to 90 slidably engage a channel bar within and without the window sill to space the brackets and move the tops of the brackets into the same horizontal plane.

5. A sleeping porch adapted to be secured to a window sill comprising a spaced 95 bracket made up of a horizontal beam member and a supporting brace, said beam having an inwardly and downwardly extending hooked portion formed on its inner end, horizontal channel bars transverse to the 100 beam member and on both sides of the window sill, complementary perforations in the beam and brace member adapted to receive a securing bolt providing approximate adjustment of the beam and brace member, 105 and adjusting screws slidably within the channel bars for providing an auxiliary adjusting means for the beam and brace member.

In witness whereof I have hereunto set 119 my hand and seal at Memphis, Tennessee, this 6th day of October, A. D. nineteen hundred and nineteen.

IRENE NORMAN. [L. S.]
